UNITED STATES PATENT OFFICE.

ROBERT T. JOHNSTON, OF CHICAGO, ILLINOIS, ASSIGNOR TO THE GOSS PRINTING PRESS COMPANY, OF CHICAGO, ILLINOIS, A CORPORATION OF ILLINOIS.

TRANSFERRING DEVICE FOR STEREOTYPE-PLATES.

1,147,733.

Specification of Letters Patent.

Patented July 27, 1915.

Application filed July 28, 1913. Serial No. 781,548.

To all whom it may concern:

Be it known that I, ROBERT T. JOHNSTON, a citizen of the United States, residing at Chicago, in the county of Cook and State 5 of Illinois, have invented certain new and useful Improvements in Transferring Devices for Stereotype-Plates, of which the following is a specification.

My invention relates to apparatus for 10 operating upon stereotype-plates in their preparation for application to rotary printing-presses, and it has more particularly to do with mechanism for transferring such plates from the casting apparatus to the 15 mechanism by which they are finished.

The object of my invention is to provide mechanism by which the plate, after it has been cast and before the tail-piece or riser has been severed from it, may be seized, by 20 its riser end and lifted out of the case of the casting box, and turned over and deposited on its side edges upon a suitable stand or table, from which it may be transferred to any suitable finishing apparatus.

25 I accomplish this object as illustrated in the drawings and as hereinafter described.

What I regard as new is set forth in the claims.

In the drawings,—Figure 1 is a side elevation illustrating my invention, the casting box being shown in conventional form. It will be understood that the casting box illustrated is of the common type in which there is a fixed or stationary core, and a pivotally-mounted case which co-operates therewith, and is adapted to be turned into a vertical position to receive the molten metal, and to be turned to a substantially horizontal position after the cast has been made and prior to the removal of the plate. Fig. 2 is a plan view of the parts shown in Fig. 1, most of the stand or table being broken away; and Fig. 3 is an end view of the casting apparatus and the plate transferring device.

Referring to the drawings,—4 indicates the core of the casting-box, and 5 the shell or case thereof, which is suitably pivoted, preferably as shown in patent No. 933,172, dated Sept. 7, 1909, to Samuel G. Goss, so that it can swing into operative relation with the core, or may be turned down to the position shown in Fig. 1. When in the

latter position, the case is open at the top and at its right-hand end, and after a cast 55 has been made the plate lies in the case with its side margins uppermost and the tail-piece or riser at the right-hand end of the case, as is well understood by those familiar with the art. 60

6 indicates laterally-projecting handles provided at the sides of the case for convenience in swinging it.

7 indicates a roller which I provide at the open end of the case, said roller extending transversely of the case and having its periphery concave to correspond with the outer or printing surface of the stereotype-plate, as shown in Fig. 3, so that when the plate is drawn out of the open end of the 70 case it will rest upon said roller. The roller is placed slightly above what is the bottom of the case when it is turned to a horizontal position, so that the plate is lifted slightly when drawn out, and consequently does not 75 rub or scrape the case.

8 indicates the stand or table to which the stereotype-plate 9 is transferred.

10 indicates standards mounted on a suitable base 11, which preferably is also the 80 base of the casting-box, as shown in Fig. 1. The standards 10 are at opposite sides of the case, being set a sufficient distance apart so that the plate 9 may pass between them. 12 indicates a shaft, which is mounted in suitable bearings 13, carried by the standards 10, as shown in Fig. 2.

14 indicates cranks mounted on the ends of the shaft 12 for rocking it.

15 indicates arms or lugs carried by the 90 shaft 12, adjacent to the bearings 13, said arms being adapted to align with the upturned side edges of the stereotype-plate 9 when the same is drawn out of the case. The arms 15 are preferably at right angles 95 with the cranks 14, so that when the cranks are in a vertical position, as shown in Fig. 1, the arms 15 are in a horizontal position, at which time they are parallel with the side edges of the stereotype-plate, and are 100 so placed that the plate may be shoved out under them, so that said arms then rest upon the side edges of the plate, as shown in Fig. 1.

16 indicates a bent arm, which is secured 105 substantially centrally to the shaft 12, and

is in position to project under the central portion of the tail-piece when the plate is moved out of the casting-box, in the manner shown in Fig. 1. Thus when the plate is moved out to engage the transferring device, the side margins of the tail-piece lie immediately under and engage the arms 15, and the arm 16 projects under the central portion of the tail-piece, so that the three arms coöperate to engage the tail-piece in such manner that by rocking the shaft 12 the stereotype-plate may be swung up and over, in the manner indicated by dotted lines in Fig. 1. The table 8 is placed in such position that when so swung the free end of the plate rests upon it. As the plate is turned over in this operation, it will be observed that the plate will rest on the table 8 upon its side edges. The plate may then be shoved out of engagement with the lifting device, leaving the latter free to be restored to its normal position for the reception of another plate.

In order to hold the plate-engaging device in its normal position and also to limit its movement in one direction, I provide a standard 17 arranged in alinement with the arm 16 and having a spring-stop 18, which is adapted to engage a lug 19, carried by said arm 16, when the lifting device is in its normal position. This stop, however, owing to its spring construction, is adapted to move back out of operative position when the cranks 14 are operated to rock the shaft 12, but at other times it engages the lug 19 with sufficient force to prevent accidental displacement of the lifting device.

From the foregoing description it will be noted that the transferring device engages only the tail-piece, and consequently there is no danger of damaging the printing surface of the plate. Furthermore, while the lifting device is arranged in proper position to receive the plate from the case after the cast has been made, it is entirely distinct from the casting apparatus and does not interfere with or affect the operation of the latter in any respect, so far as the casting of the plate is concerned. By the use of my improved apparatus, the plate does not have to be handled except to the extent of moving it out of the casting apparatus far enough to engage the arms 15-16, and consequently the transferring of the plates to the table 8 is greatly facilitated, as owing to their shape and to the fact that they are very hot when just cast, it is quite inconvenient and unpleasant to transfer them from the casting-box by hand.

So far as I am aware, I am the first in the art to provide means separate from the casting apparatus for engaging a stereotype-plate and transferring it from the casting apparatus, or a transferring apparatus arranged to swing transversely of the plate,

or one which engages the end of the plate. The claims hereinafter made, are, therefore, to be construed accordingly.

That which I claim as my invention, and desire to secure by Letters Patent, is,—

1. A transferring device for stereotype-plates, comprising means independent of the casting apparatus for engaging the plate, said engaging means being movable to lift the plate out of the casting apparatus and transfer it to a suitable support. 70

2. A transferring device for stereotype-plates, comprising means independent of the casting apparatus for engaging the plate, said engaging means being movable to lift 80 the plate out of the casting apparatus, invert it, and deposit it upon a suitable support.

3. A transferring device for stereotype-plates, comprising rocking means independent of the casting apparatus and having devices adapted to engage and retain the plate while it is lifted out of the casting apparatus by the rocking of said transferring device. 85

4. A transferring device for stereotype-plates, comprising swinging means adapted to engage one end portion of the plate, said engaging means being adapted to swing to lift the plate out of the casting apparatus 90 and transfer it to a suitable support.

5. A transferring device for stereotype-plates, comprising swinging means adapted to engage one end portion of the plate, said engaging means being adapted to swing to 100 lift the plate out of the casting apparatus, invert it, and transfer it to a suitable support.

6. A transferring device for stereotype-plates, comprising a rock-shaft mounted on 105 a suitable support, and means carried by said shaft adapted to engage an end portion of the plate and hold the same while said shaft is rocked to lift the plate out of the casting apparatus. 110

7. A transferring device for stereotype-plates, comprising a rock-shaft mounted on a suitable support, arms carried by said shaft adapted to aline with and bear against the side margins of the plate when the latter 115 is moved out of the casting apparatus, and an arm carried by said shaft and adapted to centrally engage the outer end portion of the plate whereby said arms coöperate to hold the plate while said shaft is rocked to 120 lift it out of the casting apparatus.

8. A transferring device for stereotype-plates, comprising a rock-shaft having means adapted to engage an end portion of the plate and hold it while it is being lifted 125 out of the casting apparatus, and a stop for holding said transferring device normally in operative position.

9. A transferring device for stereotype-plates, comprising a rocking member having 130

means for engaging an end portion of the plate when the latter is moved out of the case of the casting apparatus, and means operatively related to said rocking member for lifting the plate slightly when it is moved out of the casting apparatus.

10. The combination with a stereotype-plate casting box, comprising a core and a case, said case being arranged to turn to a substantially horizontal position, of a transferring member arranged opposite the open end of the case when the latter is in its horizontal position, said transferring member having rocking means adapted to engage an end of the plate and hold it while it is lifted out of the case.

11. The combination with a stereotype-plate casting box, comprising a core and a case, said case being arranged to turn to a substantially horizontal position, of a transferring member arranged opposite the open end of the case when the latter is in its horizontal position, said transferring member having rocking means adapted to engage an end of the plate and hold it while it is lifted

out of the case, and a roller carried by the case and arranged between the case and the transferring member for lifting the plate slightly when it is moved out of the case into engagement with said transferring member.

12. A transferring device for stereotype-plates, comprising means adapted to swing about an axis arranged transversely of the plate, said means having devices adapted to engage one end of the plate and hold it while it is lifted out of the casting apparatus and transferred to a suitable support.

13. The combination with a stereotype-plate casting box having a pivoted case, of a transferring device comprising a member independent of the case and adapted to swing about an axis parallel with the pivotal axis of the case, and having means for supporting the plate while the same is lifted out of the case by the swinging of said transferring device.
